(57) **CLAIM**

The ornamental design for a tent, as shown and described.

DESCRIPTION

FIG. 1 is a front, left and top perspective view of a tent, showing our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 of FIG. 1 thereof;

FIG. 10 is an enlarged view of portion 10 of FIG. 1 thereof;

FIG. 11 is an enlarged view of portion 11 of FIG. 1 thereof; and,

FIG. 12 is a front, left and top perspective view of the tent of FIG. 1 shown with environment in a state of use.

The broken lines in the drawings show portions of the tent that form no part of the claimed design. The additional broken lines shown in FIG. 12 are directed to environment and form no part of the claimed design.

1 Claim, 12 Drawing Sheets
